UNITED STATES PATENT OFFICE.

LUTTRELL H. STUART, OF CHICAGO, ILLINOIS.

ATTACHING-PLUG FOR ELECTRIC WIRES.

SPECIFICATION forming part of Letters Patent No. 681,461, dated August 27, 1901.

Application filed May 1, 1901. Serial No. 58,294. (No model.)

To all whom it may concern:

Be it known that I, LUTTRELL H. STUART, a citizen of the United States, residing at Chicago, in the county of Cook and State of Illinois, have invented certain new and useful Improvements in Attaching-Plugs for Electric Wires; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to attaching-plugs for electric wires, and particularly to plugs used in connection with electric lamps.

One object is to construct an attaching-plug by means of which wires may be connected 20 to an ordinary electric-lamp socket or fixture, so as to permit the lamp to be moved about or used away from the socket.

A further object is to provide means for doing this without twisting the wires, which 25 is inconvenient and apt to injure or break the wires and interrupt the circuit.

The drawings illustrate the invention as applied to an ordinary Thomson - Houston lamp-socket.

30 Figure 1 is a plan view with the socket partly broken away. Fig. 2 is a longitudinal section showing the plug detached, part of the socket being broken away. Fig. 3 is a plan view of the inner face of the plug; and Fig. 4 is a sectional plan on the line 4-4, Fig. 2.

The socket is indicated at 5, having the usual metallic ring 6, forming one terminal, and the externally-screw-threaded extension 12, forming the other terminal.

40 My plug is formed of two parts or blocks of insulating material, the inner block 7 connecting with the socket and the outer or wire-carrying block 7^a connecting with the wires. These blocks are connected rotatably relative 45 to each other by an axial screw-rod 14, passing loosely through both blocks.

The inner face of the block 7 is provided with a metallic ring 8, adapted to contact with the ring 6 of the socket, and is also provided with 50 a squared metallic block 13, which is loosely seated in the plug and is internally-screw-threaded to receive the extension 12 of the

socket and connects with the inner end of the rod 14, which extends loosely through both blocks of the plug. The contiguous faces of the parts 7 and 7^a are provided with contact-rings 9 and 10, respectively. Rods 15 connect the ring 8 with the ring 9 through the block, and similar rods 17 connect the ring 10 with the terminals 11, to either one of which 60 may be connected one of the circuit-wires. The other terminal 16 is connected to the rod 14.

In use the plug is placed within the socket, and the inner block 7 is screwed upon the extension 12. This has the effect, when the rings 6 and 8 come together, of drawing and binding the parts of the plug together by means of the rod 14, loosely extending through the blocks, and causes close contact between the 70 rings 9 and 10 and 6 and 8. It will be seen that when the block 7 is turned the rod 14 turns in the outer block 7^a, which remains stationary, and consequently the wires attached thereto are not twisted. The current 75 can pass from the terminal ring 6 through the ring 8, rod 15, rings 9 and 10, and rod 17 to the terminal 11 and from the terminal 12 through the block 13 and rod 14 to the terminal 16.

Having thus described my invention, what 80 I claim as new, and desire to secure by Letters Patent, is—

1. An attaching-plug for electric wires comprising two blocks of non-conducting material, one of which is rotatable relative to the 85 other, and two insulated circuit-conductors extending through both blocks.

2. An attaching-plug for electric wires comprising two blocks of non-conducting material, one of which is rotatable relative to the 90 other, a connecting-rod passing through both blocks and forming one circuit-conductor, and rods passing through each block and adapted to electrically contact and form the other circuit-conductor.

3. An attaching-plug for electric wires formed of two blocks of non-conducting material one of which is adapted to turn upon a rod extending through both blocks, which rod forms one circuit-conductor, contact-rings on 100 the contiguous faces of the blocks, and conducting-rods connected to the rings and extending through the blocks and forming the other circuit-conductor.

4. An attaching-plug for electric wires comprising a block of non-conducting material having the rod 14 extending therethrough and adapted to engage one socket-terminal, and
5 having a conducting-rod and contact-ring adapted to engage the other socket-terminal, and a wire-carrying block of non-conducting material rotatably mounted on the rod 14, having a conducting-rod and contact-ring

adapted to form electric connection with the 10 conducting-rod of the other block.

In testimony whereof I affix my signature in presence of two witnesses.

LUTTRELL H. STUART.
